a proper number of intake valves and exhaust valves (not shown) are provided. Instead, however, of operating said valves by means of push rods and rocker arms, said valves are 5 operated in the desired timed relation by overhead cam shafts 25 and 26. These cam shafts, two for each cylinder group, are disposed in parallelism and have an over-all length sufficient to span the total number of 10 cylinders comprised in each cylinder group. In Fig. 3 it will be noted that the cam shafts 25 and 26 are mounted in suitable bearings 27 fastened to cylinder head cover plates 28 which are in turn fastened to the cylinder 15 heads. Said cover plates 28 are preferably of one piece construction and are adapted to bridge the space between the cylinders of the respective groups and at the forward end of said groups are adapted to overhang the 20 group series to provide housings 29 within which suitable gearing 30 for the cam shafts is enclosed. Cover plates thus characterized reinforce the cylinders of each cylinder group and at the same time provide an adequate attachment surface to which the cam shaft 25 housings 31 are fastened. A valve gear of the character herein disclosed is essential. At speeds exceeding 2000 R. P. M. push rods and rocker arms, due to inertia forces, are 30 incapable of continued operation for periods of long duration.

The means for driving the cam shafts 25 and 26 (in addition to the gearing 30) comprises a plurality of radially arranged drive 35 shafts 32 which, at their outer ends, enter the cover plate overhangs. Said shafts 32 at their inner ends are carried into the crank case 10, each shaft having mounted on said inner end a bevel gear 33 which meshes with 40 a similar gear 34 mounted on the engine crank shaft. Each said drive shaft is operated at the desired speed of rotation, due to its geared connection with the crank shaft, and in its relation to the cylinder group 45 which it serves, extends radially out from the crank shaft in line with the radial plane of its associated cylinder group.

As is customary in aeronautical internal combustion engines, a certain number of engine accessories are essential to the proper 50 operation of the engine herein described. Such accessories include a carburetor 35, a fuel pump 36, an oil pump assembly 37, two distributors 38-38, a magneto 39, an engine starter 40, and a generator 41. Preferably such accessories are grouped radially about 55 an extension 42 of the crank case 10 so that any or all of such accessories may be removed or replaced with as little inconvenience as 60 possible. The crank case extension 42 is fastened to and against a rear end blower or compressor 43, the latter, as indicated in Fig. 4, being directly fastened to the rear end of the crank case. Said blower 43, which is 65 directly driven off the crank shaft 12, is so

formed and constructed as to provide within the crank case extension 42 a fuel induction passage 44. This passage 44 is open at one end to the carburetor 35 and at its opposite end widens outwardly to form the casing 70 within which the blower 43 is enclosed. From said blower casing the fuel mixture is fed radially to the cylinder intake ports 22 thru the intake manifolds 24.

In addition to driving the blower 43, the 75 crank shaft 12, thru its rear end driving terminal 14, is directly geared as at 45 to a counter-shaft 46. This counter-shaft 46 has an axis of rotation parallel with the axis of rotation of the crank shaft tho it is enclosed 80 for the major part within the blower casing and the crank case extension 42. Intermediately of its ends said shaft 46 has splined thereon a spiral gear 47, and upon its rear end a bevel gear 48. At each side of said counter-shaft 46 and directly driven off the worm gear 47, there is provided a vertical shaft 49. Said vertical shafts 49, which extend parallel, are journaled at their opposite ends in 85 bearings 50, and at one end are extended beyond the underside of the crank case extension wall. One of said shafts has mounted at its extended end the fuel pump 36, whereas the other of said shafts is still further extended to drive the oil pump assembly 37; 90 said pumps 36 and 37, like the carburetor 35, being fastened exteriorly of the crank case extension on the underside of its bottom wall. As illustrated in Fig. 5, the shafts 49 are located one each at opposite sides of the 95 fuel induction passage 44. Transversely extending stub shafts 51-51, geared as at 52, one each to each vertical shaft 49, extend laterally out from the fuel induction passage 44 to drive the distributors 38 which are mounted exteriorly of and against the opposite side 100 walls of the crank case extension 42.

The magneto 39 and the engine starter 40 are also mounted exteriorly of and against 110 the opposite side walls of said crank case extension. The driving connection for said accessories 39 and 40 consists of a transverse shaft 53 having a bevel gear 54 mounted thereon and meshing with the bevel gear 48 mounted on the end of the shaft. Said accessories 39 and 40, however, are disposed in a horizontal plane above the corresponding plane of the shafts 51 and in a transverse vertical plane longitudinally removed from the 115 transverse vertical plane of the vertical shafts 49. Moreover, if desired, by the provision of a vertical stub shaft and bevel gear (not shown) the generator 41 may be likewise driven off the bevel gear 48. Preferably 120 said generator 41 is mounted on the exterior top side of the crank case extension 42. Bolts 55, grouped radially about the crank case extension, and carried by the blower 125 casing, provide an appropriate mounting

PAPER-DISPENSING MACHINE

Application filed May 23, 1931. Serial No. 539,474.

This invention relates to improvements in dispensing apparatus and has particular reference to a machine of the type wherein a continuous web of paper is fed to a cutter 5 to be severed thereby into predetermined lengths.

An object of the invention is to provide an improved machine of practical construction in which a continuous web of paper is fed to 10 a cutter which is operated, by the means which feeds the paper thereto, to sever said web into predetermined lengths.

Another object is to provide the machine with two web-feeding devices so that different 15 predetermined lengths of paper may be fed to a cutter, either of said devices being effective to control the operation of said cutter.

The above and other objects will appear more clearly from the following detailed 20 description, when taken in connection with the accompanying drawings, which illustrate a preferred embodiment of the inventive idea.

In the drawings—

Figure 1 is a top plan view of the machine 25 constructed in accordance with the invention, with the cover of the casing thereof removed;

Figure 2 is a longitudinal section taken on the line 2—2 of Figure 1;

Figure 3 is a transverse section on the line 30 3—3 of Figure 1;

Figure 4 is a similar section on the line 4—4 of Figure 1;

Figure 5 is a section on the line 5—5 of 35 Figure 1, showing one of the feeders in its fully-operated position;

Figure 6 is a fragmentary longitudinal section illustrating one of the feeders at the termination of its feeding movement and the beginning of the movement thereof which is 40 utilized to operate the cutter; and

Figure 7 is a section on the line 7—7 of 45 Figure 1.

The present machine is especially designed for dispensing parchment paper or the like, 45 such as used in stores for providing inner wrappers for food products, but it is to be expressly understood that the machine is not limited to such use, the scope of the invention being defined by the appended claims.

The machine comprises a casing 10 hav-

ing a removable cover 11 and front and rear walls 12 and 13. Mounted upon the side walls 14 adjacent the rear of the casing are opposed brackets 15 vertically slotted, as indicated in dotted lines in Figure 2, to receive the ends of a free-floating shaft 16 which carries the continuous web of paper 17 in the form of a roll which rests upon the bottom of the casing at all times as the diameter of the roll decreases. The web of paper is fed on to a guide in the nature of a platform 18 supported within the casing longitudinally thereof and having its rear end disposed directly above the roll of paper. The platform 18 extends to a point adjacent 60 the front wall 12 of the casing which is provided with an outlet 19 through which severed sheets are withdrawn from the casing, and the forward portion 20 of said platform is inclined downwardly for a purpose which 65 will appear in the course of the description. In order to properly guide the web of paper, the longitudinal edges of the platform are doubled upon themselves to provide overhanging flanges 21 which form channels for 70 receiving the longitudinal edges of said web. Substantially coextensive with the platform 18 and along the longitudinal edges thereof there are supported tracks 22 and 23, the entire length of each of which is in the same 75 plane so that the forward end of the track will be elevated above the inclined portion 20 of the platform.

In the track 22 there is mounted for sliding movement longitudinally thereof a feeder 80 generally indicated by the numeral 24, while in the track 23 a similarly constructed feeder 25 is mounted for sliding movement. These feeders are alternatively used for feeding different lengths of the web 17 along the 85 platform 21 to a cutter to be later described and, for this purpose, said feeders are disposed in normal positions at different distances from the forward end of said platform, so that the movement of either feeder 90 along its track to a point contiguous to the rear end of the inclination 20 of the platform will advance a different length of the web 17 to the cutter than that which is advanced 95 by the other feeder.

Each feeder comprises a shoe 26 slidable in its track and having an operating lever 27 pivotally connected thereto and projecting through a longitudinal slot 28 formed in the cover 11 with its outer end adapted to be grasped in a hand of the operator when it is desired to obtain a severed sheet from the machine. Extending inwardly from the lever 27 of each feeder and overhanging the platform 18 is an arm 29, the inner end of which has secured thereto a gripper member 30 of rubber or any other suitable material which, in the normal position of the lever 27, is slightly raised above the web 17, but which is adapted to engage said web when the lever is thrown rearwardly about its pivot, which is the initial operation preparatory to advancing the web toward the cutter. When the lever is thus operated, a coil spring 31 connecting the same with its shoe 26 is compressed so that, upon release of the lever by the operator at the conclusion of the operation, said lever is restored to its normal position and the gripper 30 again disengaged from the web. In its normal position the feeder is prevented from rearward movement along its track by a stop member 32 in the form of a wire or small rod having its ends bent for insertion into any one of a series of opposed pairs of openings 33 in the track of the feeder. This stop member is adjustable to any position along the track so as to vary the normal position of the feeder, whereby the same may be caused to advance any predetermined length of the web.

Means are provided in connection with each feeder for restoring the same to its normal position against its stop member 32, following its forward movement along the track thereof and the release of the lever 27 by the operator. This means comprises a flexible band or tape 34, one end of which is connected to the shoe 26 of its respective feeder, said band extending rearwardly from said shoe and over an idler 35 at the rear end of the feeder track. From this idler the band extends to a drum 36 mounted upon the base of the casing 10 and upon which said band is wound. A spring 37 is coiled within the drum and its outer extremity connected thereto, while the inner end thereof is secured upon a shaft 38 projecting from said drum. This shaft has associated therewith an escapement mechanism including the ratchet 39 and pawl 40 which cooperate to hold the shaft and maintain the spring 37 under tension. By turning the end of the projecting shaft 38 in a clockwise direction, as viewed in Figure 2, the tension of the spring 37 may be increased and, by tripping the pawl 40 to permit of step-by-step rotation of the shaft 38 in an opposite direction, said tension may be decreased. It will thus be seen that, when one of the feeders is pulled forwardly by the operator after the lever 27

of the feeder has been swung rearwardly to engage the gripper member 30 with the web of paper, the latter will be advanced and at the same time the band 34 will be unwound from the drum 36, thereby putting the spring 37 under the tension necessary to automatically return the feeder to its normal position when the lever 27 has been released. As either feeder is drawn forward, during which the lever 27 thereof is held by the operator in its rearward position, the gripper member 30 continues to engage the web 17 until the rear end of the inclined portion 20 of the platform is reached. Then, as the forward movement of the feeder continues, its gripper member becomes disengaged from the web, at which instant the advance thereof toward the cutter ceases and a predetermined length is now in position to be severed. The remainder of the forward movement of the feeder to the front end of its track is utilized to accomplish the operation of the cutter and its associated mechanism which will now be described.

At the forward end of the platform 18 there is extended thereacross just below the guide flanges 21 and at the point of emergence of the web therefrom a stationary cutter bar 41, to one end of which there is pivoted, as at 42, the movable cutter 43 which, in its normal position, is raised above the platform and yieldably held in such position by a retractile spring 44, one end of which is connected to the free end of said cutter and the other end of said spring is joined to the upper end of a standard 45 secured to the base of the casing (Figures 3 and 5). Also connected to the free end of the cutter 43 is one end of a link 46, the other end of which is joined to a lever 47 pivoted, intermediate its ends as at 48, to a standard 49 also supported upon the base of the casing 10. The other end of the lever 47 engages a trip 50 in the form of a bell-crank pivoted to said standard 49 and having one end projecting into the track 23 of the feeder 25 so as to be contacted by the shoe 26 of said feeder as the latter approaches the end of its forward movement, said movement being limited by a stop member 51 similar to the members 32. Upon contact of the shoe 26 with the trip 50 the latter is rocked about its pivot and, in so doing, imparts a similar movement to the lever 47, throwing the front end thereof downwardly and pulling the cutter 43 therewith so that the latter will cooperate with the cutter bar 41 to sever the desired length of paper from the web 17, the major portion of which length is at this time projected through the opening 19 and can, following its severance from the web, be withdrawn from the machine. In order to produce a shearing action between the bar 41 and cutter 43, the latter, in its normal position, extends at a slight angle relative to the

vertical plane of the bar 41 so as to partially overhang said bar, as best indicated in Figure 1. The cutter is yieldably maintained in this position by a leaf-spring 52, the lower end of which is secured to the standard 45 while the upper portion of the spring engages the free end of the cutter 43 and forces the same rearwardly so as to position it diagonally, as previously mentioned. The tension of the spring 52, and consequently the amount of its lateral pressure against the bar 41 as the cutter is operated, may be regulated by a set-screw 53 mounted on the standard 45 and engaged with said spring. Upon release of the lever 27 from its position in Figure 5 the same is thrown forwardly by its spring 31 and simultaneously the spring 37 of the winding drum, which is at this time under tension, operates to wind the band 34 upon said drum and thus pull the feeder 26 rearwardly until it contacts its associated stop member 32. At the same time the spring 44 of the cutter 43 acts to restore the latter to its normal position.

The operation of severing a length of the web 17 by the actuation of the feeder 24 on the opposite side of the platform 18 from the feeder 25 will now be described. The web 17 is advanced in the same manner as previously described to the cutting point, whereupon the continued advancement of the feeder 24 causes its shoe 26 to contact the end of the bell-crank lever 54 which projects into the track 22. Said lever 54 is similar to the trip 50 and is pivotally mounted upon the standard 55, with its other end in engagement with the rocking lever 56 corresponding to the lever 47. The forward end of the lever 56 is connected by a link 57 to the free end of a cutter-actuating arm 58, the other end of which is pivotally connected to the standard 45. Intermediate the ends of this arm a pin 59 projects therefrom and rests upon the upper edge of the cutter 43. With this construction, when the shoe 26 of the feeder 24 rocks the bell-crank lever 54 about its pivot, the lever 56 is operated to pull down upon the link 57 and thereby cause the arm 58 to exert a downward pressure upon the cutter which then cooperates with the bar 41 to sever the web. Release of the lever 27 of the feeder 24 then permits the latter to be restored to its normal position in the same manner as described in connection with the feeder 25.

What is claimed is:

1. In a dispensing machine, a guide for a web of paper, a cutter for severing a length from said web, a feeder movable along said guide and having a normal position from which it can be engaged with said web to feed a length thereof to said cutter, means operated by said feeder after said length has been fed to said cutter for actuating the latter to sever said length from the web, and

spring tension means connected to said feeder and operable upon severance of said length to restore said feeder to its normal position.

2. In a dispensing machine, a platform constituting a guide for a web of paper and having an inclined end, a cutter at said end for severing a length from said web, a feeder movable along said platform and engageable with the web thereon to feed the same to said cutter, said feeder disengaging said web upon reaching the inclined portion of said platform, and means thereupon operable to actuate said cutter.

3. In a dispensing machine, a platform constituting a guide for a web of paper and having an inclined end, a cutter at said end for severing a length from said web, a feeder movable along said platform and engageable with the web thereon to feed the same to said cutter, said feeder disengaging said web upon reaching the inclined portion of said platform, and a mechanism thereupon operated by said feeder to actuate said cutter.

4. In a dispensing machine, a guide for a web of paper, a cutter for severing a length from said web, a track extending along an edge of said guide, a feeder movable in said track and having a gripper engageable with the web on said guide to feed said web to said cutter, and a trip mechanism for said cutter including an element projecting into said track and in the path of movement of said feeder so as to be actuated thereby.

5. In a dispensing machine, a guide for a web of paper, a cutter for severing a length from said web, a track extending along an edge of said guide, a feeder movable in said track and having a gripper engageable with the web on said guide to feed said web to said cutter, a trip mechanism for said cutter including an element projecting into said track and in the path of movement of said feeder so as to be actuated thereby, said trip mechanism further including a lever operated by said element, and an arm connected to said lever and having a bearing on said cutter to operate the same.

6. In a dispensing machine, a platform constituting a guide for a web of paper, a stationary cutting edge at one end of said platform, a cutter engageable with and movable relative to said edge to sever a length of said web, a track coextensive with said platform, a feeder movable along said track and having a gripper engageable with the web on said platform, a stop member on said track contacted by said gripper to limit the movement of the latter along said track and away from said cutter, and a trip mechanism operated by said feeder to actuate said cutter when a length of said web has been fed thereto by the movement of said feeder toward said cutter.

7. In a dispensing machine, a platform constituting a guide for a web of paper, a

stationary cutting edge at one end of said platform, a cutter engageable with and movable relative to said edge to sever a length of said web, a track coextensive with said platform, a feeder movable along said track and having a gripper engageable with the web on said platform, a stop member on said track contacted by said gripper to limit the movement of the latter along said track and away from said cutter, a trip mechanism operated by said feeder to actuate said cutter when a length of said web has been fed thereto by the movement of said feeder toward said cutter, and spring tension means connected to said feeder for moving the same away from said cutter until it contacts said stop member.

8. In a dispensing machine, a guide for a web of paper, a cutter for severing a length from said web, a feeder movable relative to said guide to feed a predetermined length of said web to said cutter, said feeder including a gripper normally out of contact with said web, means to engage said gripper with said web and to move said feeder, and means actuated by the movement of said feeder to operate said cutter.

9. In a dispensing machine, a guide for a web of paper, a cutter for severing a length from said web, a feeder movable along said guide and including a shoe, a lever pivoted to said shoe, an arm extending from said lever, a gripper carried by said arm and engageable with said web when said lever is actuated, said lever also constituting a handle for moving said feeder, and means actuated by the movement of said feeder for operating said cutter.

In testimony whereof, we have affixed our signatures.
